UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

CARRIAGE-LOCK FOR TYPE-WRITING MACHINES.

1,182,204.

Specification of Letters Patent.

Patented May 9, 1916.

Application filed February 6, 1912. Serial No. 675,772.

To all whom it may concern:

Be it known that I, OTTO PETERMANN, a citizen of the Republic of Switzerland, and a resident of Groton, county of Tompkins, and State of New York, have invented certain new and useful Improvements in Carriage-Locks for Type-Writing Machines, of which the following is a full, clear, and exact description.

10 This invention relates more particularly to locking means adapted for use in connection with foldable and visible writing machines such as shown in the patent to Frank S. Rose, No. 948,553, dated Feb. 8, 15 1910.

In machines of the type set forth in the Rose patent referred to, the carriage is mounted to travel along a bed. This bed is held upon arms, bars or members which 20 are pivoted to other bars or arms located on opposite sides of the machine and form a part of a foldable support to adapt the carriage bed and mechanism mounted thereon to be folded forward over the keyboard in 25 order that the machine may occupy less space than when in use and to permit the machine to be readily transported or for other purposes. In such machines the carriage and platen are shifted vertically by 30 key-operated mechanism to adapt the type-heads to have a plurality of characters thereon. If a sudden platen shift movement is given, the carriage and platen may move beyond the point intended and a type caused 35 to print before the carriage can return by gravity, and where the machine is used while traveling in vehicles, as railroad trains, having constant vibration, the carriage often vibrates vertically independent of any shifting 40 movement of the support and relatively to other parts of the machine. It is desirable, therefore, to hold the carriage and the support against its folding movement, and it is further desirable that some means be 45 provided for this purpose to hold the carriage and platen against folding in case the machine should, for any reason, be inverted while handling the same.

The primary object of the invention is to 50 overcome the objectionable features referred to, and to provide simple means which may be mounted upon the machine and so arranged that the foldable part of the carriage support may be held against movement unless said means is released, thus retaining 55

the carriage and the foldable part of the support against independent movement until it is desired that such parts be moved from a normal working position into compact relation to another part of the machine. 60

Another object of the invention is to provide a simple and efficient manually operated device which may be located on either or both sides of the machine and which is carried by one part of the foldable support 65 and is adapted to engage another part thereof in such a way that the parts of the support may be held detachably together.

A further object of the invention is to provide means which may be variously operated and located, and which is simple in construction and may be readily applied to machines of various kinds. 70

With these and other objects in view, the invention will be hereinafter more particularly described with reference to the accompanying drawings, which form a part of this specification, and will then be pointed out in the claims at the end of the description. 75

In the drawings, Figure 1 is a fragmentary vertical section of the rear part of a machine, showing one embodiment of the invention applied thereto; and Fig. 2 is a sectional plan view under the carriage bed, 80 taken on the line II—II of Fig. 1.

The frame 10 may have side frame members 11 and a rear frame plate 12 made of sheet metal or otherwise. A post or guide 13 may be located at each rear corner of the machine frame and adapted to move vertically in each post and be guided therein is a slide or shift rod 14. These rods 14 may be connected together by a transversely extending rod 15 at their lower ends, and held to the rod 15 is the arm 16 of a platen shift lever 17. This shift lever 17 is held to a transversely extending rod 18 serving as a pivot therefor so that when said shift lever is moved by depressing the key portion, 95 not shown, the rods 14 will be raised in the usual way. There are usually two shift levers to adapt the type-bars to have several characters thereon for figures, the upper case and lower case characters, but only 100 one shift lever is shown and simply for the purpose of illustration.

A bar or member 19 is held to the upper end of each shift rod 14 and said bars may be connected transversely of the machine by 110

a rod 20. A second bar or member 21 is pivoted at 22 to each bar or member 19 to adapt the bars 21 to be moved upward and forward on the pivot 22, the members 19 and 21 forming a foldable support. The members 21 of the support have a bed 23 secured thereto along which a carriage 24 is adapted to travel. This carriage has a platen 25 mounted thereon against which the type are adapted to strike during the printing operation, and under the carriage bed and support 21 may extend a protecting plate 26. As will be evident, the carriage, carriage bed and platen, may be shifted or moved forward with the arms 21 by reason of their pivotal connection at 22 with the arms 19, and in such a way that the platen and carriage will overhang the keyboard or be otherwise placed in compact relation to another part of the machine. The parts as thus described are substantially the same as disclosed in the patent hereinbefore referred to and may be of any suitable construction.

A device 27 is pivoted at 28 and has a tooth or projecting part 29 forming a catch which is adapted to engage under a tooth or projecting part 30 formed on the rear end of the bar or support member 19. This device 27 has its pivot 28 so positioned with relation to the tooth 29 that when moved on its pivot, the said tooth will be disconnected from the tooth 30 to permit the members 21 and carriage to be folded forward, it being understood that the device may be located on one side of the machine or on both sides of the machine as preferred. The device 27 has its body portion extending rearwardly and on the end thereof is provided with a finger part 31 by which the device 40 may be moved on its pivot or the said device may be otherwise operated. The device is provided with a lug or projection 32 on the upper edge thereof which is engaged by a spring 33, the upper end of which fits about a lug or projection 34 located under the carriage bed and which serves to hold the spring in position. This spring 34 normally forces the device into engagement with the tooth 30 when the carriage is in its normal working position. The device has a curved or recessed portion at 35 which is adapted to engage a stop 36 to limit the downward movement of said device. This stop is in the form of a screw so that the head thereof will serve to guide the device in either its upward or downward movement.

When the device 27 is in the position shown, the bars or members 19 and 21 are held against any relative independent movement, thus keeping the carriage and platen in a fixed position relatively to the other working parts of the machine. If it is desired to fold the machine to make the same more compact, all that is necessary is to

move the device 27 by taking hold of the finger part 31, thus releasing the tooth 29 from the tooth 30, the said device automatically engaging the tooth when the parts are again restored to their normal working position. 70

From the foregoing, it will be seen that very simple and efficient means is provided which may be variously constructed and adapted in such a way as to prevent relative shifting movement between the parts of the carriage support; and that said means is readily accessible to permit the folding of the support and is so constructed as to be automatic in this action to hold the members of the support against folding movement. 75 80

Having thus described my invention, I claim as new and desire to secure by Letters Patent:—

1. In a typewriting machine, the combination of a bed, a carriage adapted to travel along said bed, a support for the carriage and bed comprising foldable members, one of which has a tooth, a device pivotally held to another member and having a tooth adapted to engage the first-mentioned tooth, said device having a finger portion, a guide and stop to limit the movement of the device in one direction, and a spring interposed between the carriage bed and the device and normally forcing the device into engaging position. 90

2. In a typewriting machine, the combination of a bed, a carriage adapted to travel along said bed, a support for the carriage and bed comprising foldable members, one of which has a tooth, a device pivotally held to another member and having a tooth adapted to engage the first-mentioned tooth, said device having a finger portion, and a spring interposed between the carriage bed and the device and normally forcing the device into engaging position. 100 105

3. In a typewriting machine, the combination of a bed, a carriage adapted to travel along said bed, a support for the carriage and bed comprising bar-like foldable members pivotally held together, one of which has a tooth at one end, a device pivotally held to another member and having a tooth at one end adapted to engage the first-mentioned tooth, said device having a finger portion, a guide and stop to limit the movement of the device in one direction, and a spring interposed between the carriage bed and the device and normally forcing the device into engaging position. 110 115

4. In a typewriting machine, the combination of a platen, a foldable support having a plurality of members on a part of which the platen is mounted, means for shifting the platen vertically, and a manually operable device carried by one member of said support independent of the shift 120 125 130

mechanism but shiftable therewith and adapted to engage another member of said support to prevent relative folding movement.

5. In a typewriting machine, the combination of a support having pivoted bar-like parts foldable relatively with respect to each other, a carriage mounted on said support, a tooth located at the end of one of the non-folding parts of said support, means for shifting said support vertically, and a piv-

otally held device carried by a folding part of said support and adapted to engage said tooth when in normal working position and prevent any folding movement.

This specification signed and witnessed this 23d day of January, A. D. 1912.

OTTO PETERMANN.
